AUTOMATIC NIPPLE AND SEALING DISC RELEASING MEANS

Yervant H. Kurkjian, Clifton, N. J., assignor to Kurk Products Co., Clifton, N. J., a corporation of New Jersey

Application November 9, 1954, Serial No. 467,796

2 Claims. (Cl. 215—11)

This invention relates to automatic nipple and sealing disc releasing means, and has for one of its objects the production of a simple and efficient means for automatically breaking the vacuum seal between a nursing bottle and nipple as the nipple retaining cap is loosened upon the bottle of a nursing unit.

A further object of this invention is the production of a simple and efficient means carried by the resilient flange of a nursing nipple for automatically breaking the vacuum seal between a nursing bottle and the nipple flange when the nipple retaining cap is loosened upon the bottle of a nursing unit.

Other objects and advantages of the present invention will appear throughout the following specification and claims.

In the drawing:

Figure 1 is a perspective view of the sealing disc of the nursing unit, looking at the under face thereof;

Figure 2 is an inverted perspective view of the nipple of the nursing unit;

Figure 3 is a bottom plan view of the sealing disc;

Figure 4 is a top plan view of the nipple;

Figure 5 is a side elevational view of the nursing unit, certain parts being shown in section, the nipple and sealing disc being shown in a venting position;

Figure 6 is a similar view to Figure 3, the parts being in a vacuum sealed position;

Figure 7 is an enlarged fragmentary sectional view of the parts of the nursing unit in a venting position;

Figure 8 is an enlarged fragmentary sectional view of the parts of the nursing unit in a vacuum sealed position;

Figure 9 is a vertical sectional view of a modified form of the invention, the parts being in a venting position;

Figure 10 is an enlarged fragmentary sectional view of the form shown in Figure 9, the parts being in a vacuum sealed position;

Figure 11 is an enlarged fragmentary vertical sectional view of a further modified form of the invention;

Figure 12 is an enlarged fragmentary sectional view of the nipple showing the nipple in a locked operative position upon a bottle.

By referring to the drawing in detail, it will be seen that 10 designates a rigid container or nursing bottle which preferably is of the wide-mouth type. A flexible or elastic nipple 11 having a flexible or elastic annular vented flange 12 is shown in an inverted position in Figures 5 and 6. The nipple 11 in the inverted position, extends down into the wide mouth of the bottle 10, and the vented flange 12 in the nipple-inverted position rests upon the upper edge of the container or neck of the nursing bottle 10 when storing the container and its contents within a refrigerator or other refrigerated unit. A sealing disc 13 preferably of rigid material such as plastic and the like, rests upon the flange 12 of the inverted nipple 11. The disc 13 is preferably provided with an upstanding finger grip flange 14 upon the top face there-

2

of to facilitate the placing of the disc 13 in position. A central reinforcing portion 15 is preferably carried by the under face of the disc 13.

It has been found that when the bottle or container 10 is filled with hot or warm milk or other fluid, and is placed within a refrigerator with the flange 12 of the inverted nipple 11 and disc 13 clamped in a sealing position upon the neck of the bottle or container by means of the conventional adjustable retaining cap or ring 16, the cooling-off process of the milk or fluid within the container or bottle will build up a vacuum within the container or bottle 10. This causes the flange 12 to tightly adhere or stick to the upper edge of the neck of the container or bottle 10, and also causes the sealing disc 13 to adhere or stick to the flange 12 and thereby provide a vacuum seal, so as to make it difficult, without great effort, to release the disc 13 from the flange 12 and to release the flange from the upper edge of the neck of the container or bottle 10 after the retaining cap or ring has been loosened or removed.

In order to automatically break this vacuum seal immediately upon the loosening of the retaining cap, the resilient or rubber flange 13 is provided with a plurality of minute or relatively small resilient nibs, teats, or other protuberances 17 formed integral with the flange 12 upon the inverted face of the flange 12, near the outer edge or periphery thereof, as shown in the drawing. Likewise, a plurality of nibs, teats or other integral protuberances 18 are formed or carried by the under face of the sealing disc 13, as shown in the drawing.

When the nipple 10 is in an inverted position within the neck of a container or bottle, as shown in Figures 5 and 6, the nibs, teats, or other protuberances 17 of the flange 12 rest upon or in contact with, the upper edge 35 of the neck of the container or bottle 10, in the manner shown in Figures 5 and 7. The nibs, teats, or other protuberances 18 of the disc 13 rest upon or in contact with, the abutting face of the vented flange 12 of the nipple 11, as shown in Figures 5 and 7. As the retaining cap or ring 16 is threaded upon the neck of the container or bottle 10 to a sealing position, the disc 13 will be forced tightly upon the flange 12 and the flange 12 will be forced tightly upon the upper edge of the neck 40 of the container or bottle 10 to properly seal the neck of the container or bottle. As the contents of the container or bottle cools a vacuum is built up within the container or bottle, as is obvious. However, because of these nibs, teats, or protuberances, as soon as the retaining cap or ring 16 is loosened upon the neck of the container or bottle and removed, the nibs, teats or protuberances expand and cause the flange 12 to be released or raised from the upper edge of the neck of the bottle 10, and the disc 13 to be raised above the flange 12, thereby breaking the vacuum seal and permitting the disc 13 and flange 12 of the nipple to be easily lifted from the neck of the container or bottle.

When the cap or ring 16 is tightened to a sealing position, the nibs, teats, or other protuberances 17, because of their elastic or resilient nature, will be compressed and embedded into the inverted face of the flange 12, as shown in Figure 8. The rigid nibs, teats or other protuberances 18 of the disc 13 will be embedded into the abutting face of the flange 13, as shown in Figure 8. As soon as pressure of the cap or ring is removed or released, the elastic or resilient nature of the flange will cause the nibs, teats, or protuberances 17 to expand downwardly against the upper edge of the neck of the bottle 10 and thereby raise the inverted face of the flange 12 out of contact with the upper edge of the neck of the bottle 10 to break the vacuum seal and permit air to rush into the container or bottle. The elastic or resilient nature of the flange 12

will also cause the nibs, teats, or other protuberances 18 to be pushed outwardly, thereby raising the disc 13 out of contact with the abutting face of the flange 12 to release the vacuum seal between the parts.

In the form shown in Figures 9 and 10, the elastic or resilient flange 12^a of the nipple 11^a is provided with integral nibs, teats, or protuberances 19 upon the inverted face of the flange 12^a, and integral nibs, teats or protuberances 20 formed upon the upper face of the flange 12^a, as shown in Figure 9. A sealing disc 21 is preferably placed thereon in the nature of a retaining element in conjunction with the adjustable retaining cap or ring 16^a. When the cap or ring 16^a is tightened, the nibs, teats, or protuberances 19 and 20 will be compressed, as shown in Figure 10, to provide a proper seal. When the cap or ring 16^a is removed or loosened, the nibs, teats, or protuberances 19 and 20 will expand to separate the flange 12^a from the neck of the bottle 10^a, and the disc 21 from the flange 12^a to release the vacuum seal.

In Figure 11, the neck of the bottle 10^b is provided with a plurality of nibs, teats, or protuberances 22, which extend slightly above the bottle neck and normally support the inverted elastic vented nipple flange 12^b. As the retaining cap 16^b is tightened upon the bottle neck, the nibs, teats, or protuberances 22 will be forced into the nipple flange 12^b to seal the flange 12^b tightly upon the outer end of the neck of the bottle. When the retaining cap 16^b is removed, the elastic nature of the flange 12^b will raise the flange 12^b upon the nibs, teats, or protuberances 22 and out of contact with the upper end of the bottle neck to break the vacuum seal within the bottle 10^b. The sealing disc 13^b is interposed between the cap or ring 16^b and the bottle neck 10^b.

As shown in Figure 12, when a cap or ring 16^c is used, having a wedge shaped nipple retaining rib 22, the teats 23, similar to the teats 17, abut against the rib 22 as the cap or ring 16^a is tightened upon the bottle 24, and when the nipple 11^c is in an operative position. This rib 22 acts to retain and lock the edge of the flange 12^c of the nipple 11^c in position, so that the nipple 11^c cannot be pulled out of the cap. Therefore, the teats 23 which are inwardly spaced from the outer edge of the flange 12^c, as shown, and are located outwardly of the rib 22 to abut the rib 22, perform a two-fold function, first, as an automatic vacuum seal breaking means, as previously described, and second, as a flange locking means.

It should be understood that certain detail changes may be employed without departing from the spirit of the invention, so long as such changes fall within the scope of the appended claims.

Having described the invention, what I claim as new is:

1. In combination with a rigid container having an open outer end, a nipple having a resilient flange fitting

upon said open outer end of said container, a retaining cap adjustably secured to said container and receiving said flange to seal said flange upon the open outer end of said container, a plurality of spaced integral resilient nibs carried by said flange and contacting the outer end of said container, said nibs being compressible into said resilient flange of said nipple when said cap is adjusted upon said container to seal said flange upon said container, and said nibs being adapted to expand outwardly beyond said resilient flange when said cap is adjusted to release pressure of said cap from said resilient flange of said nipple, to thereby automatically move said resilient flange away from an out of contact with said container to automatically break the seal between the outer end of said container and said resilient flange, a rigid sealing disc carried by said cap and contacting one face of said resilient flange, said disc having a plurality of spaced small rigid nibs contacting one face of said flange when the nipple is in an inverted position to penetrate said flange to move said disc into sealing contact with said resilient flange when said cap is clamped to a sealing position upon said container, and the resiliency of said resilient flange being adapted to force said nibs out of penetrating engagement with said flange to thereby automatically separate and break the sealing contact between said disc and resilient flange when said cap is released from said container to thereby release pressure of the cap from said sealing disc.

2. In combination with a rigid container having an open outer end defining a rigid nipple flange abutment portion, a nipple having a resilient flange, a retaining cap adjustably mounted upon said container and movable to and from a flange sealing position, a rigid sealing disc carried by said cap and contacting one face of said resilient flange, said disc having a plurality of spaced small rigid nibs contacting one face of said resilient flange when the nipple is in an inverted position to penetrate said flange to move said disc into sealing contact with said resilient flange when said cap is clamped to a sealing position upon said container, and the resiliency of said resilient flange being adapted to force said nibs out of penetrating engagement with said resilient flange to thereby automatically separate and break the sealing contact between said disc and said resilient flange when said cap is released from said container to thereby release pressure of the cap from said sealing disc.
